DESIGN FOR A STOVE HANDLE

Robert F. Hefferan, Grand Rapids, Mich., assignor
to Winters & Crampton Corporation, Grand
Rapids, Mich., a corporation of Michigan

Application September 14, 1946, Serial No. 133,308

Term of patent 7 years

(Cl. D81—25)

To all whom it may concern:

Be it known that I, Robert F. Hefferan, a citizen of the United States, residing at Grand Rapids, in the county of Kent and State of Michigan, have invented a new, original, and ornamental Design for Stove Handle, of which the following is a specification, reference being had to the accompanying drawing, forming part thereof.

Fig. 1 is a perspective view of the stove handle, showing my new design.

Fig. 2 is an edge view of the same.

Fig. 3 is a side view of the same, and

Fig. 4 is an end view of the same.

The design is characterized by an enamel coating on all parts of the handle excepting the outer

surfaces of the ridges which are polished bright metal.

I claim:

The ornamental design for a stove handle, as shown and described.

ROBERT F. HEFFERAN.
